(57) **CLAIM**

The ornamental design for a notebook computer as shown and described.

DESCRIPTION

FIG. 1 is a perspective view of a notebook computer showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged detail view of portion 8 in FIG. 2; and, FIG. 9 is an enlarged detail view of portion 9 in FIG. 6.

The evenly spaced broken lines in the drawings depict portions of the notebook computer that form no part of the claimed design. The dash-dot broken lines in the drawings illustrate the boundaries of the enlarged detail views and form no part of the claimed design.

1 Claim, 7 Drawing Sheets
